Primary Examiner — Ricky Pham**CLAIM**

The ornamental design for a food blender blade, substantially as shown and described.

DESCRIPTION

FIG. 1 is a top perspective view of a blender blade in accordance with an embodiment of the present design;

FIG. 2 is an underside perspective view of the embodiment shown in FIG. 1;

FIG. 3 is a bottom plan view of the embodiment shown in FIG. 1;

FIG. 4 is a top plan view of the embodiment shown in FIG. 1; FIG. 5 is a right underside elevational view of the embodiment shown in FIG. 1;

FIG. 6 is a left side elevational view of the embodiment shown in FIG. 1;

FIG. 7 is a front underside elevational view of the embodiment shown in FIG. 1; and,

FIG. 8 is a rear elevational view of the embodiment shown in FIG. 1.

In a preferred embodiment, the nature of this product is as a blade comprising two sets of stackable blades and twelve total, which is primarily useful as a chopping means for a food blender.
